US0D1050750S

(12) **United States Design Patent** (10) **Patent No.:** **US D1,050,750 S**
(45) **Date of Patent:** **** Nov. 12, 2024**

(54) **CHAIR**

(71) Applicant: **Bestqi Innovation Technology (Shenzhen) Co., Ltd**, Shenzhen (CN)

(72) Inventor: **Xiangyu Wang**, Shenzhen (CN)

(***) Term: **15 Years**

(21) Appl. No.: **29/944,335**

(22) Filed: **May 28, 2024**

(51) **LOC (14) Cl.** **06-01**

(52) **U.S. Cl.**

USPC **D6/366**

(58) **Field of Classification Search**

USPC D6/334-336, 363-367, 379, 716-716.1,

D6/716.4

(57) **CLAIM**

The ornamental design for a chair as shown and described.

DESCRIPTION

FIG. 1 is a perspective view of a chair showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dash-dash broken lines in the drawings depict portions of the chair that form no part of the claimed design.

1 Claim, 8 Drawing Sheets
